COUNTERBALANCING DEVICE

Bernard A. Ball, Smethport, Pa.

Original application June 16, 1939, Serial No. 279,547. Divided and this application April 22, 1940, Serial No. 331,035

3 Claims. (Cl. 254—152)

This application is a division of my earlier application for patent, Serial No. 279,547, filed June 16, 1939, for Tenpin setting machines, and relates particularly to counterbalancing devices adapted for use with such machines, although this invention has more general application as well.

The principal object of the invention, therefore, is to produce a better and more active mechanism for returning the frames of tenpin setting machines to their elevated or normal positions.

Figure 1 is a perspective view of a portion of a tenpin setting machine, looking at it from the left front, and showing the counterbalancing device applied thereto.

Figure 2 is a view, partly in section, of the counterbalancing roller and its immediately co-operating parts.

Figure 3 is a view of the inside of one of the side frames, with the counterbalancing device in section, the figure being taken on the line 3—3 of Fig. 1, looking in the direction of the arrows.

Although, as stated above, the invention is of general application, it will herein be described in connection with a tenpin setting machine. Only enough of the machine, however, is shown as is necessary to illustrate the construction and operation of the counterbalance.

The pin carrier or platform proper is in general of the same construction as that shown in the patent to Backus No. 809,890, granted January 9, 1906. This has been long and successfully used, and need not be illustrated or described in detail. For the purpose of this case, it is sufficient to say that it consists primarily of a platform 10 adapted to carry the pins and provided with guides 12 pivoted to the platform, by which the pins are guided to the alley.

As heretofore constructed, pin setting machines have usually been provided with counterbalancing weights for restoring their pin platforms to normal or raised position. These weights must have a mass sufficient to overbalance and thus lift the pin platform when empty, after the tenpins have been deposited on the alley. But the action of all counterweights is sluggish, for they operate according to the laws of gravity, and so always start slowly and move with a continuously accelerated motion. In the construction of the instant case, torsion springs have been used in place of the weights of earlier machines. Springs, when under constant tension, as they will here be in practice, begin to exert their full lifting force as soon as released, and therefore are quicker in

action than weights, which operate only by gravity.

Referring to the drawings, and particularly to Fig. 2 thereof, 20 is a shaft suitably mounted for rotation in the frame of the machine, and 21 is a drum or sleeve surrounding the shaft 20 and rotatable thereon. On shaft 20 are mounted helical springs, as 22 and 26. Any number of such springs may be used. Only two are shown here, and they are illustrated as reversely wound with respect to each other; that is, they are wound one to the right and the other to the left. One end of each spring, as here shown the inner end, is fastened directly or indirectly to the shaft 20; and while this may be done in any preferred manner, I have shown the inner end 23 of the spring 22 formed into a loop 24, and the inner end 27 of the spring 26 formed into a similar loop 28, and these loops respectively secured to the shaft 20 by screws or bolts 25 and 29 which pass through the loops and into or through the shaft 20. The other ends of the springs 22 and 26 are secured to the drum 21, the outer end of the spring 22 being secured to the drum 21 by a nut 32 and the outer end of the spring 26 being secured to the drum 21 by the nut 35. The specific means for securing the ends of the springs to the shaft 20 and the drum 21 are not of the essence of the invention, and other desired means may be employed.

Cords or cables 36 and 37, of wire or other suitable material, are provided to support the pin platform. One end of each of these cables is secured to the platform, while the other end of each cable is wound directly upon the drum 21, if the same be of sufficient size, or upon an auxiliary drum, as 38 or 39, secured to the drum 21.

The drum or sleeve 21 is mounted on the shaft 20 by means of collars; in Fig. 2, the right hand end of the drum is secured to a bushing 45, which in turn is mounted for free rotation on the shaft 20, and the left hand end is secured to a bushing 46, which likewise is mounted to rotate freely on shaft 20. As here shown, a washer 47 of suitable thickness is placed between the bushing 46 and the left hand end of the frame of the machine. A collar 48, secured on the right hand end of the shaft 20, and outside the frame, prevents the end of the shaft from slipping through the frame.

On the left hand end of the shaft 20, Figs. 1 and 2, is arranged a ratchet wheel 50, having on the periphery thereof teeth 51, and secured to the shaft 20 in any convenient way, as by a pin 52, so as to turn with the shaft. A lever 53,

carrying a floating pawl 54, is rotatably mounted on the hub 55 of the ratchet wheel 50; and a holding pawl 56, pivoted at 57, cooperates with the ratchet teeth to hold the ratchet against rotation. One end of the shaft 20 is shaped as at 58 to receive a wrench for turning the shaft, so that the springs 22 and 26 may be put under tension. In practice, the approximate tension is put upon the springs 22 and 26 by the use of this wrench; but the shaft may also be turned by the lever 53 and floating pawl 54, and minor adjustments are usually made in this manner. The shaft is held in the desired position by means of the holding pawl 56.

The rotation of the shaft 20, either by means of the squared head 58 or by the lever and pawl 53, 54, will simultaneously put tension on both springs. In practice, the springs should be so tensioned that they will be able to lift the pin platform quickly and positively when the platform is unloaded, but will permit the platform when carrying the pins to fall freely of its own weight, or with only slight additional pressure by the operator. Experience must determine the proper tension.

By this construction, the main operating springs 22 and 26 may be wound simultaneously, and therefore wound with fewer turns of the shaft 20 than is possible where a single long spring is employed. Moreover, as stated above, a quicker and more effective action is secured with a plurality of short springs than with a single long spring.

While the springs are here shown as connected to the shaft 20 at their inner ends, and to the drum 21 at their outer ends, it is to be understood that of course this arrangement may be reversed, and the outer ends connected to the shaft and the inner ends to the sleeve.

As stated above, the counterbalancing device 40 herein described and claimed, while of general application, is shown in conjunction with a ten-pin setting machine. This machine is used merely to illustrate the invention, and is not claimed herein, but is described and claimed in said parent application Serial No. 279,547, filed June 16, 1939, of which this is a division. It will, however, be well to describe the machine shown in general terms.

The pin setter comprises, in general, two side frames, each constructed, as here shown, of Z-iron uprights 61 and 62, and crosspieces 63 and 64. There may be as many crosspieces as necessary, but only two are shown in the drawings. The top crosspieces 63 are each provided with an enlargement or extension 65, through which the shaft 20 of the counterbalancing means passes. The collar 48 on the shaft 20 cooperates with the outer face of this enlargement 65 on the right hand side of the machine, Fig. 2, while the ratchet wheel 50 is secured to the end of the shaft outside the extension 65 at the other side of the machine.

These side frames may be supported in any convenient way relative to the alley, but are here shown as supported by the divisions between alleys, usually termed kickbacks. The supporting devices are in the nature of brackets 70 having their upper ends attached to the Z-irons of the frame and their lower ends secured to the kickbacks 60. In as much as these form no part of the present invention, it is thought unnecessary that they be here described further.

A beam 35, Fig. 1, connects the two side frames and is secured thereto in any suitable way.

Braces 88, running from the side frames to the cross beam 35, give the necessary lateral strength to the framework. Bars 92 one secured to the members of each side frame by screws or bolts 93 add rigidity to the structure. These bars at their lower ends are bent transversely at 94 and again at 95, so as to offset the lower ends thereof for a purpose to be later explained.

Arranged to slide on each side frame are supplemental frames comprising members 100, 101, and crosspieces 102 and 103, with diagonal braces 104 and 105. To these supplemental frames are secured brackets 111 which support the pin platform proper. Thus, as the supplemental slides are moved up and down in the frames, the brackets which are secured thereto carry the pin platform 10 in its movements toward and away from the alley. The construction of the supplemental slides and of the guideways therefor is novel, but since this arrangement is not involved in this application, it is not necessary that it be more particularly described.

In order to lower and raise the pin platform manually, or to aid in the lowering and lifting of the same, a manual operating mechanism is shown in Figs. 2 and 3. It is necessary in pin setting machines to have some such supplemental operating mechanism, because the weight carried by the platform may vary greatly under operating conditions. If the counterbalancing mechanism is adjusted to take care of the whole complement of pins, it will not function properly when the machine is operated with only a portion of the pins in place; for if only a portion of the pins are on the platform, they will not be of sufficient weight to overcome the counterbalancing device, and a manual supplemental operating mechanism is needed. For this purpose, the machine illustrated is provided with a hand bar 130 running across the upper portion of the frame where it can be conveniently grasped by the operator. This bar has rollers 131, one on each end thereof, normally resting on wear plates 132 secured to the side frames of the machine. Bars 133 one on the inside of each side frame are attached at their outer ends to the bar 130, and have their other ends mounted with a sliding connection on the lower ends of the bars 92. This sliding connection is merely an elongated slot 134 and pin connection 135. Each auxiliary sliding frame has attached thereto a channel bar 136, or its equivalent, and operating in each channel is an antifriction roller 138, carried by and pivoted on the bar 133. These rollers, as the handle 130 is moved up and down, move back and forth in the channels 136.

Normally, the pin platform 10 is in raised position, being held in this position both by the tension of the springs and by the locking action of the handle bar upon the wear plates. Assuming the pin platform to be loaded, if the handle bar 130 is drawn off the wear plates 132, the pin platform 10 will move down of its own weight, and simultaneously will wind up the torsion springs 22 and 26. When the pins shall have been deposited on the alley, the pin platform, due to the extra tension put upon the torsion springs 22 and 26, and the loss of the pin load, will be automatically raised by the springs until the handle bar 130 reaches its highest position, and its ends come to rest on the wear plates 132. But if the pin platform does not have upon it a full complement of pins, and the handle bar 130 is moved off the wear plates 132, the weight of the pin platform together with the weight of

the pins will not be sufficient to lower the platform against the tension of the torsion springs, and it will then be necessary not merely to draw off the handle 130 but to press down on the same, and thus effect the positioning of the pins manually.

As the handle bar 130 moves down and up, it is to be understood that the rollers 138 carried by the arms 133 move back and forth in the channel bars 136, and in so doing lower and raise the supplemental side frames, which, in turn, through the brackets 111, lower and raise the pin platform.

The springs 140, of which two are shown, are buffers for absorbing the shock of the pin platform and associated parts as the platform is returned to raised position.

Having now described the principles of my invention, I claim:

1. A counterbalancing mechanism comprising a shaft normally stationary but adapted to be turned, a drum surrounding the shaft and mounted to rotate with respect thereto, load supporting means adapted to be wound upon the drum, a plurality of helical springs surrounding the shaft and within said drum and having their ends secured to axially spaced points on the drum and shaft respectively, so that a relative movement of the shaft and the drum in one direction will simultaneously tension all of the springs, and the springs when not restrained will provide a relative movement of the shaft and the drum in the other direction.

2. A counterbalancing mechanism comprising a shaft normally stationary but adapted to be

turned, a drum surrounding the shaft and mounted to rotate with respect thereto, load supporting means adapted to be wound upon the drum, a pair of oppositely wound helical springs surrounding the shaft and within said drum, adjacent ends of the oppositely wound springs being secured to the shaft and the other ends of the springs being secured in axially spaced relation to the drum, so that a relative movement of the shaft and the drum in one direction will simultaneously tension all of the springs, and the springs when not restrained will provide a relative movement of the shaft and the drum in the other direction.

3. A counterbalancing mechanism comprising a shaft normally stationary but adapted to be turned, a drum surrounding the shaft and mounted to rotate with respect thereto, load supporting means adapted to be wound upon the drum, helical springs in oppositely wound pairs surrounding the shaft and within said drum, and means for turning the shaft to vary the tension in the springs and means for locking the shaft to hold the springs under tension, adjacent ends of the springs of each pair being secured to the shaft in axially spaced relation to the adjacent ends of each other pair and the opposite ends of the springs of each pair being secured in axially spaced relation to the drum, so that a relative movement of the shaft and the drum in one direction will simultaneously tension all of the springs, and the springs when not restrained will provide a relative movement of the shaft and the drum in the other direction.

BERNARD A. BALL.
